PROTECTOR FOR DRILL PIPE AND THE LIKE

Filed May 27, 1929

UNITED STATES PATENT OFFICE

JOHN W. MACCLATCHIE, OF COMPTON, CALIFORNIA

PROTECTOR FOR DRILL PIPE AND THE LIKE

Application filed May 27, 1929. Serial No. 366,264.

This invention is a protector for the various strings of casing, drill pipe and the like which are adapted for lowering into a well during development and production, and has for its object to provide a simple but practical protector which is particularly adapted for mounting on a string of drill pipe so as to provide protection between the drill pipe and the surrounding well casing; it being apparent however that the protector may be adapted for mounting on any string of pipe or well tools which is adapted to be lowered in a well bore, and reference herein to a protector for drill pipe will thus be understood as embodying the mounting of a protector on any type of well string.

It is a further object of the invention to provide a protector which will insure a yieldable cushioning engagement between a string of well pipe and the wall of the surrounding bore which may be formed by a string of well casing or the like, with the protector adapted to maintain its cushioning engagement irrespective of the various conditions of hard usage which may be encountered in the well bore.

More particularly it is an object of the invention to provide a protector comprising a sleeve of yieldable cushioning material such as a resilient medium, rubber for example, with the cushioning sleeve longitudinally split for readily encircling a drill pipe and having retaining means surrounding the split sleeve for preventing its displacement from the drill pipe, with the retaining means preferably arranged whereby the sleeve is held against radially outward expansion but is adapted for radially inward expansion so as to tightly grip the drill pipe and thus prevent axial displacement of the protector.

It is a further particular object of the invention to provide for positively drawing the retaining means into tight gripping engagement with the protecting sleeve, and to preferably arrange said positive tightening means

for locking engagement with the drill pipe so as to prevent its displacement and thus insure the retaining means maintaining a tight gripping engagement.

Further objects of the invention will be readily understood from the following description of the accompanying drawing, in which:

Fig. 1 is a fragmentary side elevation of a string of drill provided with the protector which is shown partly in axial section.

Fig. 2 is a detail axial section on the line 2—2 of Fig. 1, showing operative position of the tightening means for gripping the protector on the drill pipe.

Fig. 3 is a fragmentary view similar to Fig. 2 but showing the tightening means prior to its shifting to operative position.

The protector is illustrated as mounted on a string of drill pipe 1 having usual coupling collars 2, and the protector comprises a sleeve 3 of rubber or the like forming a yieldable cushioning medium adapted to encircle pipe 1 with its outer contact periphery 4 projecting radially outwardly beyond couplings 2 so that the protector sleeve will receive the impact of any abutment against the wall of the surrounding well bore, and will thus prevent any wear of either the drill pipe or the well casing or the like which forms the surrounding bore. The outer contact periphery of the cushioning sleeve may taper to reduced diameters toward its respective ends as shown in Fig. 1, so that the string of drill pipe may be inserted and withdrawn without liability of the protector catching on any obstruction in the well bore.

In order to provide for convenient mounting of the protector sleeve at any desired point between couplings 2, the sleeve is preferably longitudinally split as shown at 5 so that it may readily encircle pipe 1, and the split sleeve is held in operative position surrounding the drill pipe by retaining means 6 encircling the sleeve and preferably compris-

ing non-expansible annuli seating in the outer peripheral surface of the sleeve so that any radial expansion of the sleeve must be radially inwardly for tightly gripping the sleeve on the drill pipe. As an instance of this arrangement the outer periphery of sleeve 3 may be circumferentially grooved as shown at 7, preferably adjacent the respective ends of the sleeve, and one or more coils of 10 a suitable non-expansible but readily pliable wire 8 is received in each of the grooves 7 so as to encircle the split sleeve 3, with the ends of each wire suitably connected, as for example by a twisted engagement 9. The 15 wires 8 thus hold the protector sleeve against swinging open at its split 4 and thus retain the sleeve on drill pipe 1, and the non-expansible wires by engaging the outer peripheral surface of the protector sleeve insure all radial expansion of the sleeve being radially inwardly so as to maintain a gripping engagement of the protector on the drill pipe.

The wires 8 when in operative position may be positively tightened for more firmly gripping the protector sleeve on the drill pipe, and said positive tightening means may be arranged for locking engagement with the drill pipe so as to positively hold the protector against axial displacement. For this 25 purpose a key 10 is adapted for longitudinal insertion in the split 5 of sleeve 3 so as to extend under wires 8 as shown in Fig. 3, and the outer face of the key forms wedging surfaces 11 adapted to slide down in back of the 30 respective wires 8 so as to positively tighten the same, with the wires preferably seating in notches 12 in said outer face of the key when the latter has been shifted to position for maximum wedging tightening of the 35 wires as shown in Fig. 2.

The key 10 when wedged in back of wires 8 preferably provides a positive locking engagement with the drill pipe 1 for preventing axial displacement of the protector sleeve, 40 and for this purpose the inner face of the key may be toothed or serrated as shown at 13, so that with the key in operative position as shown in Fig. 2 the teeth 13 will bite into the drill pipe 1 for preventing axial displacement of the protector sleeve or relative 45 axial shifting of the key in a direction to release its wedging engagement with wires 8.

The protector sleeve is thus adapted for 50 convenient mounting on a drill pipe at any desired point along its length, and is positively held against axial displacement, with the retaining wires insuring all radial expansion of the sleeve being radially inwardly for radially increasing the gripping engagement of the sleeve on pipe 1, and the key 10 providing a wedge for positively tightening the wires 8 and adapted to bite into the drill pipe for positively locking the key against axial displacement from its operative 55 position.

In practice a relatively large number of coils of the wire 8 are preferably received in each of the grooves 7, with the wire which is received in each groove preferably comprising one continuous wire passed around the protector sleeve to form an initial coil, the ends of which are then twisted together as shown at 9^a, with the ends of the twisted wire then again passed around the protector sleeve to form succeeding coils, the ends of each of which are similarly twisted together before forming the next succeeding coil, in order that the one continuous wire which is thus coiled around the sleeve at each groove 7 shall comprise a plurality of annular retaining means, each individually fastened in place, so that breakage of one or more coils of the wire will leave the remaining coils fastened in place for securing the protector sleeve on the drill pipe. 80

I claim:

1. A protector comprising a sleeve adapted to encircle a drill pipe, retaining means encircling the sleeve, and a wedge adapted for insertion beneath the retaining means for tightening the same so as to radially contract the sleeve for gripping engagement on the pipe. 90

2. A protector comprising a sleeve adapted to encircle a drill pipe, a non-expansible closed annulus encircling the sleeve so as to prevent radially outward expansion of the sleeve, and a wedge adapted for insertion beneath the closed annulus for tightening the same so as to radially contract the sleeve for 95 gripping engagement on the pipe. 100

3. A protector comprising a sleeve axially split so as to adapt it to encircle a drill pipe, retaining means encircling the split sleeve, and a wedge adapted for insertion beneath the retaining means for tightening the same so as to radially contract the sleeve for gripping engagement on the pipe. 105

4. A protector comprising a sleeve axially split so as to adapt it to encircle a drill pipe, a non-expansible closed annulus encircling the sleeve so as to prevent radially outward expansion of the sleeve, and a wedge adapted for insertion beneath the closed annulus for tightening the same so as to radially contract the sleeve for gripping engagement on the pipe. 110

5. A protector comprising a sleeve axially split so as to adapt it to encircle a drill pipe, retaining means encircling the split sleeve, and a key adapted for longitudinal insertion in the split of the sleeve and beneath said retaining means, said key having a wedging surface adapted to engage the retaining means for tightening the same, and the key having an opposite surface adapted for locking engagement with the pipe. 115

6. A protector comprising a sleeve axially split so as to adapt it to encircle a drill pipe, retaining means encircling the split sleeve, 120

and a key adapted for longitudinal insertion in the split of the sleeve and beneath said retaining means, said key being adapted for locking engagement with the pipe.

5 7. A protector comprising a sleeve axially split so as to adapt it to encircle a drill pipe, a key in said split adapted for locking engagement with the drill pipe, and retaining means encircling the split sleeve and adapted

10 to tighten the key against the drill pipe.

In testimony whereof I have affixed my signature.

JOHN W. MacCLATCHIE.
